US00D782621S

(12) **United States Design Patent** (10) **Patent No.:** **US D782,621 S**
(45) **Date of Patent:** **** Mar. 28, 2017**

(54) **SIDE LOAD CONDUIT CONNECTOR**

(71) Applicant: **Bridgeport Fittings, Inc.**, Stratford, CT (US)

(72) Inventor: **Lawrence J. Smith**, Stamford, CT (US)

(73) Assignee: **BRIDGEPORT FITTINGS, INC.**, Stratford, CT (US)

(**) Term: **15 Years**

(21) Appl. No.: **29/553,057**

(22) Filed: **Jan. 28, 2016**

(57) **CLAIM**

The ornamental design for a side load conduit connector, as shown and described.

DESCRIPTION

FIG. 1 is a rear perspective view of a side load conduit connector;

FIG. 2 is a left side view of the side load conduit connector, the right side being a mirror image thereof;

FIG. 3 is a bottom view thereof;

FIG. 4 is a top view thereof;

FIG. 5 is a front view thereof; and,

FIG. 6 is a rear view thereof.

1 Claim, 3 Drawing Sheets
